UNITED STATES PATENT OFFICE.

HARRY W. DENGATE, OF BEDFORD, OHIO.

CARBURETION MEANS.

Application filed September 9, 1925. Serial No. 55,225.

My invention relates generally to devices for cleaning and for moistening air and particularly to such devices associated with or related to carbureting devices.

5 The main objects of my invention are:— first, a simple and efficient means for cleaning as well as moistening air to be used for carburetion purposes; second, to prevent water from mixing bodily with the carbureted air 10 in the carbureting device; third, to prevent condensation of the moisture in the air between the air moistening means and the outlet end of the carbureting means; fourth, to clean and to moisten the air before it reaches 15 the water in the carbureting device; fifth, to provide means on such an apparatus for showing the state of the interior of the apparatus; sixth, to provide adjusting means for the water level in the apparatus as well 20 as for the suction chambers thereof.

It is well known, for instance, that, in many instances an internal combustion engine using gasoline and associated with an automobile having a carburetor for the gasoline, works much better in cool and moist air than in hot and dry air. Since free air is taken into the carburetor, it appears that such an engine could be operated better in all kinds of free air conditions when some means 25 is provided thereon or connected therewith to supply the carburetor with moist air. My invention aims to supply such carburetors, or other similar devices, with air having the requisite amount of moisture incorporated 30 therein.

35 My invention is illustrated in the accompanying drawing in which Fig. 1 is a sectional perspective view of an apparatus embodying the features of my invention showing the air cleaning and moistening device associated with a carburetor and with a water receptacle and also showing a water gage and a float and a valve means to regulate the water level and adjusting means for the chambers 40 associated with the cleaning and moistening device. Fig. 2 is a section taken on a horizontal plane indicated by the line 2—2 in Fig. 1 and shows more clearly the mounting of the spacers and the relations of the hood 45 and the receptacle and the spacers.

50 Similar reference characters refer to similar parts throughout the views.

Applicant is aware that modifications may be made, within the scope of the appended 55 claims, in the form and in the arrangement

of elements and that a less number of elements may be used with corresponding reduction in convenience of manufacture or operation.

Referring now particularly to the drawing:—

The cleaning and moistening device of the apparatus shown has the water receptacle A provided with the free air intake 10 which is open at each end. The cap B is secured to 65 the upper end of the receptacle A.

The hood C is disposed within the receptacle A and has the flange 11 extending all around the same and spaced from the inside of the wall 12 to provide the passage-way 13. 70 The spacers H, three in the present instance, are seated in sockets provided in the flange 11 and contact the wall 12 to keep the hood C in central position and thereby retain the space or passage-way 13 of equal width all 75 around; this is an advantage but not an absolute necessity.

The lower end of the hood C is provided with the inclined radial flange 14 to form an abutment wall for the water as will appear 80 presently and is also provided with the tubular portion 15 extending below the flange 14 for the purpose appearing presently.

The upper end of the cap B is provided with the hollow ball 16 in communication 85 with the interior of the cap B through the neck 17. The tube 18 connects the hollow of the ball 16 with the air intake end of the carbureting element or device D. The tube 18 is here shown in a long arcuate sweep to prevent condensation of the moisture in the air 90 as will appear presently.

The rod 19 has the lower end thereof secured to the upper end of the hood C and passes through the neck 17 and through the ball 16 and has the upper end thereof threaded for the adjusting nuts 20. By means of the nuts 20, the hood C can be lowered to decrease the volume of the chamber 21 and increase the volume of the chamber 22, or 100 the hood can be raised to increase the volume of the chamber 21 and decrease the volume of the chamber 22 for purposes appearing presently.

The water gage E is attached to the side 105 of the cleaning and moistening device to show the stage of the water level in the receptacle A.

The float receptacle F has the bottom there- 110 of associated with the receptacle A. The

float 23 is disposed within the receptacle F and has the rod 24 extending upward and through the cap 25 and is threaded at the upper end for the adjusting nuts 26 one of which has the pins 27 projecting from two sides thereof to engage the forked end 28 of the lever 29 for the purpose appearing presently.

The water supply tank G, either a tank or 10 a radiator or other device, has the outlet 30 for one end of the pipe 31 and the float receptacle F has the inlet 32 for the other end of the pipe 31.

Intermediate the ends of the pipe 31 is 15 the valve 33 having the stem 34 projecting upward and operatively connected to the outer end of the lever 29 which lever is fulcrumed at 35 on the standard 36.

The relief valve 37 is provided on the cap B 20 to relieve either excessive vacuum or excessive pressure in the chambers 21 or 22.

As to operation:—

The water gage E shows the stage of the water level in the receptacle A.

25 By means of the nuts 26, the flow of water from the tank G to the float receptacle F, through the valve 33, can be adjusted to maintain a certain water level in the receptacle A.

30 By means of the nuts 20, the hood C can be lowered or raised to increase or decrease the volumes of the chambers 21 and 22 and thereby adjust the suction in these chambers to suit the carburetor D or other device and to 35 suit different degrees of moisture to be imparted to the air flowing through the receptacle A.

When a suction is created in the chamber 22 40 through the carburetor D, the air in the chamber 21 has a tendency to equalize or relieve that suction but, in order to reach the chamber 22, the air from the chamber 21 must pass through the water since the flange 15 projects into the water. After this air has 45 passed through the flange 15 and through the water, it passes upward and, eventually finds its way through the space or passage 13 and into the chamber 22 and out through the pipe 18 and to the carburetor D.

50 The suction created in the chamber 22 and consequently in the chamber 21, also creates a suction in the tube 10 and thereby causes free air to enter the chamber 21 through the tube 10.

55 In order to prevent the water from passing through the space 13 bodily, I prefer to form the flange 14 as shown so that the water can abut thereon and be thrown back into the receptacle A.

60 In order to mitigate the possibility of water being raised bodily, I prefer to make the inner area within the flange 15 smaller than the area of the flange 14 so that the air passing from the chamber 21 into the water has a more 65 violent contact with the water while it is

traveling into and through it than while it is leaving it.

In general, the air enters the chamber 21 through the tube 10, then travels through the water in the receptacle A, then rises upward through the space 13 and into the chamber 22, and then through the pipe 18 and into the carburetor D.

In the present arrangement of the elements shown, condensation of moisture in the air 75 within the apparatus is taken care of. Whatever moisture is condensed in the ball 16 travels downward naturally and into the cap B through the neck 17; and whatever moisture is condensed in the chambers 21 and 22 naturally finds its way down into the receptacle A. By the time the moistened air reaches the upper end of the pipe 18, practically all condensation is complete and there is little likelihood that any solid water will reach the pipe 80 18 and whatever condensation takes place in the pipe 18 and enters the carburetor is not of serious disadvantage to the operation of the carburetor.

While the air is traveling through the water, all foreign substances, such as sand, dust, etc., are separated from the air and are retained by the water and eventually find their way to the bottom of the receptacle A 95 where they can do no damage and from where they can be removed readily. While the air is so traveling through the water, it also absorbs a certain amount of the water and thereby becomes moist air.

This apparatus, then, provides the cleaned 100 air as well as the moistened air most advantageous for the purpose desired and delivers the cleaned air to the carburetor and thereby prevents foreign substance from reaching the carburetor through the air and delivers the 105 moistened air to the carburetor before it is mixed with a volatile hydrocarbon substance and prevents condensed moisture from reaching the carburetor.

I claim:—

1. An apparatus of the character described including a receptacle partly filled with liquid, and having liquid inlet means and mixture outlet means and for maintaining the level of said liquid at a desired height in said receptacle, a hollow hood means in said receptacle located above and spaced from said level, a tubular member diametrically smaller than said hood means depending from said hood means and terminating in an open end 115 below said level, and a gas inlet tube diametrically smaller than said tubular member extending through the same and into and terminating in an open end in the hollow of said hood means.

2. An apparatus of the character described including a receptacle partly filled with carburetion liquid, a mixture outlet for said receptacle, a hollow hood in said receptacle, and means to convey carburetion gas into 130

said hood; said hood comprising a shell formed of a main portion and a depending portion, the latter terminating in an open end of less area than said main portion, and 5 said hood suspended in said receptacle so that said main portion is located above and spaced from the level of said liquid and said open end is located in said liquid.

3. An apparatus of the character described 10 including a receptacle partly filled with carburetion liquid, liquid inlet means, mixture outlet means, a hollow hood in said receptacle and having a main portion having a member filling the major portion of said receptacle cross-sectionally and a diametrically reduced portion depending from said main portion, said hood being closed all around except at the outer end of said depending portion, means for holding said hood in said 15 receptacle so that said main portion is located above and spaced from the level of said liquid and said outer open end is located in said liquid, and means for feeding carburetion gas into said main portion.

25 4. An apparatus of the character described including a receptacle partly filled with liquid, liquid inlet means, mixture outlet means, means for maintaining the level of said liquid at a desired height in said receptacle, 30 a hollow hood suspended in said receptacle above and spaced from said level and having a tubular member in communication with said hollow of said hood and extending downwardly and terminating in said liquid in an 35 open end to convey gas from said hood into said liquid below said level of less cross-sectional area than said hood, and a gas inlet pipe extending through said tubular member and spaced from the wall thereof to form a 40 passageway for said gas and terminating in an open end in said hood and above said level.

5. An apparatus of the character described 45 including a receptacle partly filled with liquid, liquid inlet means, mixture outlet means, means for maintaining the level of said liquid at a desired height in said receptacle, a hollow hood suspended in said receptacle above said level and having an arched top wall and a conical bottom wall and a tubular 50 member extending downwardly from said conical wall and terminating in an open end below said level, and a gas inlet pipe extending through said tubular member and spaced from the wall thereof and terminating in an 55 open end in said hood above said level and opposite said arched wall.

6. An apparatus of the character described 60 including a receptacle partly filled with liquid, liquid inlet and mixture outlet means, means for maintaining the level of said liquid at a desired height in said receptacle, a gas inlet pipe extending into said receptacle and through said liquid therein and terminating in an open end above said level, and a 65 baffle means suspended in and from the top

of said receptacle and having a depending member telescoping over said open end of said gas inlet pipe and spaced therefrom radially and terminating in a diametrically reduced open end below said level. 70

7. An apparatus of the character described including a receptacle partly filled with liquid, liquid inlet means, a cap on said receptacle and having a hollow neck in communication with the interior of said cap and a hollow ball in communication with said neck and a mixture outlet extending from said ball, a hood in said cap and extending into said liquid, a rod having one end thereof secured to said hood and the other end thereof extending through said neck and through said ball and supported on said ball, and a gas inlet pipe entering through the bottom of said receptacle and extending into and opening into said hood. 80

8. An apparatus of the character described 85 including a receptacle, liquid inlet means, mixture outlet means, a hood in said receptacle dividing the same into two chambers, a gas inlet means adapted to feed gas into said hood, said hood having a radial flange spaced from the inner surface of the wall of said receptacle to form a restricted passage between said chambers and having a plurality of sockets therein, and a spacer in each 90 of said sockets and projecting therefrom and contacting said inner surface to centralize 95 said hood in said receptacle.

9. An apparatus of the character described 100 including a receptacle, gas and liquid inlet means, mixture outlet means, a hood in said receptacle dividing the same into two chambers, a gas inlet means adapted to feed gas into said hood, said hood having a radial flange spaced from the inner surface of the 105 wall of said receptacle to form a restricted passage between said chambers and having a plurality of sockets therein, a spacer in each 110 of said sockets and projecting therefrom and contacting said inner surface to centralize 115 said hood in said receptacle, a rod having one end thereof secured to said hood and the other end thereof slidably longitudinally through the top of said receptacle, and a nut threaded onto said other end of said rod to support said hood in said receptacle and to permit said hood to be adjusted longitudinally in said receptacle to vary the volume of each of said chambers. 120

10. A carburetion means including a liquid 125 inlet means, a mixture outlet means, a receptacle partly filled with liquid, a baffle means in said receptacle above the level of said liquid therein and having a restricted tubular member terminating in an open end below said level, a gas inlet pipe extending into said baffle means through said tubular member thereof and terminating in an open end in said baffle means and above said level, and all of the walls of said baffle means direct- 130

ed toward said liquid to promote the drainage of said baffle means and to convey drainage directly to said liquid.

11. A carburetion means including a liquid inlet means, a mixture outlet means, a receptacle partly filled with liquid, a baffle means in said receptacle above the level of said liquid therein and having a restricted tubular member terminating in an open end below said level, a gas inlet extending into said baffle means through said tubular member thereof and terminating in an open end in said baffle means and above said level, means for adjusting said baffle means longitudinally in said receptacle to vary the depth of said open end of said tubular member below said level, and means associated with said receptacle and adapted to feed liquid into said receptacle and to maintain said level at a desired height.

12. A carburetion means including liquid inlet means, mixture outlet means, a receptacle partly filled with liquid, a baffle means in said receptacle above and spaced from the level of said liquid therein and having a diametrically reduced tubular member terminating in an open end below said level, means for adjusting said baffle means longitudinally

in said receptacle to vary the depth of said open end of said tubular member below said level, means for discharging gas into said baffle means above said level, means associated with said receptacle and adapted to feed liquid into said receptacle and to maintain said level at a desired height, and means for adjusting said associated means to vary said level.

13. A carburetion means including liquid inlet means, mixture outlet means, a receptacle partly filled with liquid, a baffle means in said receptacle above the level of said liquid therein and having a restricted tubular member terminating in an open end below said level, means for adjusting said baffle means longitudinally in said receptacle to vary the depth of said open end of said tubular member below said level, a gas inlet pipe extending into said baffle means through said tubular member and spaced therefrom radially and terminating in an open end above said level, means associated with said receptacle and adapted to feed liquid into said receptacle and to maintain said level at a desired height, and means for adjusting said associated means to vary said level.

HARRY W. DENGATE.
